ATTORNEY.

UNITED STATES PATENT OFFICE.

CHARLES T. STEVENS AND EDWIN S. DELAPLANE, OF ST. LOUIS, MISSOURI, AS
SIGNORS, BY MESNE ASSIGNMENTS, TO ATHLETIC HEALTH CHAIR COMPANY, OF
ST. LOUIS, MISSOURI, A CORPORATION OF MISSOURI.

EXERCISER.

Application filed November 27, 1922. Serial No. 603,569.

To all whom it may concern.

Be it known that we, CHARLES T. STEVENS and EDWIN S. DELAPLANE, citizens of the United States, residing at the city of St. Louis, in the State of Missouri, have invented certain new and useful Improvements in Exercisers, of which the following is a specification.

This invention is an improvement of the subject-matter of the patent to William E. Lauer for exerciser filed August 18, 1921, Patent No. 1,456,317. It is to be understood that the device herein shown and described can be used in the same manner as the device illustrated and described in the said Lauer patent, but that the construction herein shown and described embodies improvements thereover.

In the accompanying drawings forming part of this specification, in which like numbers of reference denote like parts wherever they occur,

Figure 1 is a side elevation of this device when arranged to be used as an exerciser;

Figure 2 is a side elevation thereof when set up as a chair; and

Figure 3 is a front elevation of such chair.

While useful for the purposes set forth in the said Lauer patent, this device is more or less in the way in small apartments, and in the plain form shown in the said Lauer patent, may be so unornamental as to be unwelcome in the ordinary living rooms of a home. The principal object of the present invention is to provide the Lauer apparatus with an ornamental form, so that it can be kept in any living room, and also so to construct that device that it will be useful as a chair when not in use as an exerciser.

Further features of invention are found in the necessary alteration of structure to accomplish the aforesaid purposes and in the addition of exerciser rings, the use of which is made possible with this device by reason of the addition to the Lauer device of the chair feature.

All the parts of this device are formed, shaped, and finished in such a manner as to constitute the same when set up as a chair a beautiful and ornamental piece of furniture having all the appearance of a high-class chair, the alternative use of

which can not be detected from a front view 55 of the chair and which can hardly be suspected from a side view thereof and which can be clearly perceived only from a rear view or from seeing the device laid down as an exerciser in the manner shown in 60 Figure 1.

The base 1 constitutes the chairback. The legs 2 extend therefrom and are preferably integral therewith.

The legs 3 extend from the seat-support 65 4, but not so far as legs 2. Extensions 5 are attached by hinges 6 to legs 3. By means of the extensions 5 the legs 3 are lengthened, so as to correspond with the length of legs 2, so that when the device 70 is used as a chair it will stand as shown in Figures 2 and 3. When used as an exerciser in the manner shown in Figure 1, the extensions 5 hang down and out of the way, as plainly shown in Figure 1. 75

The legs 3 contain grooves 7, in which a projection 8 from seat 9 fits. This is so that the user can sit on seat 9 when exercising in the manner provided for in Figure 1. A similar groove 10 in seat-support 4 receives projection 8, and allows seat 9 to occupy the position shown in Figures 2 and 3 when the device is to be used as a chair. 80

Braces 11 steady legs 3 when used as a chair, and form a supporting post therefor when used in the manner shown in Figure 1. Brace 12 ties legs 3 together. Brace 13 does the same for extensions 5. 85

Seat-support 4 is firmly attached to base 90 1. By this means and the braces 11, 12, and 13, a firm structure either for a chair or an exerciser is provided.

When a person using this device as an exerciser, is seated upon seat 9 in the position shown in Figure 1, his toes will be held in toehold 14, which is preferably formed of a strap or band with a buckle 15 or the like, which toehold 14 is removable when not in use as an exerciser, so that it will not mar the appearance of the device as a chair. The holders 16 for the toehold 14 are placed on the back of the chair, so that they cannot be seen from the front. There is a plurality of these at different distances from the seat 9, so as to allow for adjustment for people whose length of leg is not the same. 100 105

The exerciser can bend his head back to the floor near the outer end of legs 2 and return to an upright position without danger of tilting the base 1 in either direction, due to the fact that the length of the legs 2 beyond seat 9 operates as tilt-resisting means.

Rings 17 and elastic or spring cords 18 are mounted on the back of the chairback 10 or base 1, so as to be out of sight when not in use, and this form of exercise known as pull cords can be used with the device when in the position shown in Figure 1 or in the position shown in Figures 2 15 and 3. The holders 16 for the toehold 14 are located in a part 19 dished or countersunk in the chairback or underneath side of the base 1, so that the device can lie flat on the floor in the manner shown in Figure 1. The holders 16 are preferably arranged in pairs, the near member of each of the said pairs only being shown in Figures 1 and 2.

Having thus described this invention, we 25 hereby reserve the benefit of all changes in form, arrangement, order, or use of parts, as it is evident that many minor changes may be made therein without departing from the spirit of this invention or the scope of 30 the following claims.

We claim:

1. An exercising apparatus embodying the construction of a chair having legs, the front legs of the chair being formed of hinged 35 sections with the upper sections rigid with the bottom of the chair, the lower hinged sections of the front legs dropping to a vertical position when the chair is laid on its back for use as an exercising apparatus 40 and a seat detachable from the chair bottom and adapted to be horizontally positioned upon the rigid sections of the front legs.

2. An exercising apparatus embodying the construction of a chair having legs, the front 45 legs of the chair being formed of hinged sections with the upper sections rigid with the bottom of the chair, the lower hinged sections of the legs being for the purpose of supporting the device as a chair in one position and automatic removal out of the way 50 in another position when the chair is laid on its back for use as an exerciser.

3. An exercising apparatus comprising a

base convertible into a chair back, and having a tilt resisting extension forming an 55 integral part of the chair back and base, a seat support adapted to selectively hold a seat in two positions in planes transverse to each other and said seat support including forward legs having hinged outer ends with 60 the leg sections aligned when the apparatus is in chair position.

4. An exercising apparatus embodying the construction of a chair having a seat, back and legs, and having a tilt resisting extension forming an integral part of the back of the chair, a seat adapted to be selectively used in two planes and a removable extension embodying forward collapsible legs connected with the said seat and adapted for 70 removal out of the way when the chair is laid on its back for use as an exerciser.

5. An exercising apparatus embodying the construction of a chair, having a back, rear legs, a seat support and front legs, and a 75 seat selectively mounted on the seat support and front legs when the chair is respectively set up as a chair and laid on its back for use as an exerciser.

6. An exercising apparatus embodying the 80 construction of a chair, having a back, rear legs, a seat support and front legs, a seat selectively mounted on the seat support and front legs when the chair is respectively laid on its back and set up as a chair, and the 85 front legs having lower hinged sections adapted to drop to a vertical position when the chair is laid on its back as an exercising apparatus with the seat mounted on the rigid sections of the front legs.

7. An exercising apparatus embodying the 90 construction of a chair, having a back, rear legs, a seat support and front legs, a seat selectively mounted on the seat support and front legs when the chair is respectively laid on its back and set up as a chair, the seat 95 being positioned inwardly of the outer ends of the front legs when the chair is laid on its back and said front legs being constructed to displace the outer ends of the front legs. 100 with respect to the seat.

In testimony whereof we hereunto affix our signatures.

CHARLES T. STEVENS.
EDWIN S. DELAPLANE.
